US00D845169S

(12) **United States Design Patent** (10) **Patent No.:** **US D845,169 S**
(45) **Date of Patent:** **** Apr. 9, 2019**

(54) **UNMANNED AERIAL VEHICLE**

(71) Applicants: **BEIJING JINGDONG SHANGKE INFORMATION TECHNOLOGY CO., LTD.**, Beijing (CN); **BEIJING JINGDONG CENTURY TRADING CO., LTD.**, Beijing (CN)

(72) Inventors: **Yanjun Cui**, Beijing (CN); **Chengbin Liu**, Beijing (CN)

(73) Assignees: **BEIJING JINGDONG SHANGKE INFORMATION TECHNOLOGY CO., LTD. (CN)**; **BEIJING JINGDONG CENTURY TRADING CO., LTD. (CN)**

(**) Term: **15 Years**

(21) Appl. No.: **29/606,737**

(22) Filed: **Jun. 7, 2017**

(30) **Foreign Application Priority Data**

Dec. 9, 2016 (CN) 2016 3 0603905

(51) LOC (11) Cl. **12-07**

(52) U.S. Cl.

USPC **D12/16.1**; D12/326

(58) **Field of Classification Search**

USPC D12/16.1, 319, 325, 326, 327, 328, D12/329-345; D21/436, 441, 442, 443, D21/444, 445-453

CPC B64C 39/024; B64C 2201/141; B64C 2201/00; B64C 2201/108

See application file for complete search history.
